(57) CLAIM

The ornamental design for a lamp, as shown and described.

DESCRIPTION

FIG. 1 is a front view of a lamp, showing my new design; FIG. 2 is a rear view thereof; FIG. 3 is a right side view thereof; FIG. 4 is a left side view thereof; FIG. 5 is a top view thereof; and, FIG. 6 is a bottom view thereof.

The broken lines in the drawings illustrate portions of the lamp that form no part of the claimed design.

1 Claim, 5 Drawing Sheets
